UNITED STATES PATENT OFFICE.

JOHN M. J. WERNERT, OF PAW PAW, MICHIGAN.

DOOR.

SPECIFICATION forming part of Letters Patent No. 278,066, dated May 22, 1883.

Application filed January 15, 1883. (No model.)

To all whom it may concern:

Be it known that I, JOHN M. JOS. WERNERT, of Paw Paw, in the county of Van Buren and State of Michigan, have invented new and useful Improvements in Doors; and I hereby declare that the following is a full, clear, and exact description thereof, reference being had to the accompanying drawings, which form a part of this specification.

10 This invention relates to certain new and useful improvements in doors, particularly designed for churches and other public buildings.

15 The object of this invention is to so hang the door that it can open or swing in either direction and be readily opened in case of an emergency; and the invention consists in the peculiar construction, arrangement, and combination of the parts, all as more fully herein-
20 after set forth.

Figure 1 is a perspective view of my door, and Fig. 2 is a cross-section on the line *xx* in Fig. 1.

A represents the door-frame, and B the door.

25 The rear edge of the door has rigidly secured to it a round post, *a*, into the ends of which are secured in any convenient manner the pintles *b*, which are designed to engage in suitable holes at the top and bottom of the
30 door-frame, the round post of the door, when the latter is in place, entering a similarly-shaped recess, which is formed in the face of the door-jamb for that purpose. For the purpose of giving greater rigidity to the door the upper and lower edges thereof may have secured to them an iron strap, *c*. In hanging a door in this manner it will swing in either direction, and when wide open will stand at right angles to its post. When it is desired to have
40 the door swing so that it will shut flat back against the wall, it may be set near the corner of the door-jamb, which should be slightly recessed to allow of a free turn of the post.

C are locking-bolts, the inner ends of which are secured to the lever D, which is pivotally 45 secured to the door, said bolts sliding in proper guides to keep them in their proper position, and one or both of them may be provided with a spring, E, to keep the bolts projecting so that they will automatically lock themselves 50 when the door is closed.

A plate, F, is pivotally secured at one end to the door by means of hinge or other suitable device, while its opposite end is provided with an arm or detent, G, which engages with 55 the lower side of the lever D, such detent entering a recess cut in the wall of the door to receive it, and a suitable spring is placed between this plate and the door.

In practice, supposing the doors to be closed 60 and locked by the bolts, if there is an accident sufficient to cause a rush of the occupants of the building to the doors they would crowd against them with sufficient force to prevent their being unlocked, were they not provided 65 with this plate or similar device upon which the pressure or force of the crowd is brought to bear, causing it to close against the door and compelling its detent to raise the lever and withdraw the bolts from their fastenings. 70

While I have described but one door, it is evident that in double doors each should be provided with this device and hung in this manner.

What I claim as my invention is— 75

In combination with a door and frame constructed substantially as described, the bolts C, lever D, plate F, and detent G, when constructed, arranged, and operating substantially in the manner and for the purposes specified. 80

JNO. M. JOS. WERNERT.
